RAILROAD CROSSING STRUCTURE

Charles H. Rennels, Woodworth, Ohio

Application May 10, 1954, Serial No. 428,496

6 Claims. (Cl. 238—8)

This invention relates to a railroad crossing structure and more particularly to a resilient unit of a size and shape enabling it to be positioned in self-retaining relation between the rails and on the ties of a railroad track.

The principal object of the invention is the provision of an improved railroad crossing structure that will yieldably support vehicles and the like crossing the railroad and at the same time conform to the movement of the railroad track on which it is supported.

A further object of the invention is the provision of a railroad crossing structure comprising a pad of resilient material formed on and secured to a metal back rendering the pad of resilient material capable of bridging the area between the ties of a railroad track and supporting crossing traffic thereover.

A still further object of the invention is the provision of a railroad crossing structure which may be readily installed on spacing members on the ties of the railroad track so as to completely cover the ties between the rails of the railroad track.

A still further object of the invention is the provision of a railroad crossing structure comprising a reinforced resilient pad having means by which the pad may be anchored to the tie structure of the pad, if desired.

The railroad crossing structure disclosed herein comprises an improvement over the railroad crossing construction shown in my co-pending application for patent Serial No. 376,011, filed August 24, 1953. The railroad crossing construction disclosed in my earlier application for patent related primarily to a relatively thick slab of resilient material having a reinforcing member midway between its upper and lower surfaces.

The present disclosure relates to a more practical and commercially feasible form of the invention in that the improved structure disclosed herein is lighter in weight, easier to install and capable of more economical manufacture than the earlier disclosed construction.

Additionally, the problem of anchoring the structure to the supporting ties of the railroad track and more accurately to spacing members positioned thereon, has been satisfactorily settled in that any conventional type of spike, screw or bolt may be employed with the presently disclosed structure.

As set forth in the earlier application, the railroad crossing structure disclosed therein and the improvement thereof disclosed herein comprises a solution to the problem of establishing a satisfactory grade crossing structure on railroads.

The several constructions of the prior art have the common failing in that they adversely effect the proper ballasting of the railroad track and constitute hazards for the operating equipment due to their lack of conformation with the track structure and/or their ability to ride therewith and adjust themselves to the flexing motions of the track. Such tracks as known in the prior art have, therefore, commonly failed and resulted in rough or broken and dangerous crossings both to the operating

2

equipment of the railroad and to the vehicles crossing the railroad track.

The present improvement in such structures incorporates the several advantages of the crossing construction disclosed in my earlier application and at the same time incorporates other features rendering the structure commercially feasible and easy to install and remove, as desired.

With the foregoing and other objects in view which 10 will appear as the description proceeds, the invention resides in the combination and arrangement of parts and in the details of construction hereinafter described and claimed, it being the intention to cover all changes and modifications of the example of the invention herein 15 chosen for purposes of the disclosure, which do not constitute departures from the spirit and scope of the invention.

The invention is illustrated in the accompanying drawing, wherein:

20 Figure 1 is a top plan view of a railroad track showing the crossing structure in position.

Figure 2 is a cross section taken on line 2—2 of Figure 1.

25 Figure 3 is an enlarged detailed cross section of a portion of the construction shown in Figure 2.

Figure 4 is an enlarged detail top elevation of a portion of the construction shown in Figures 2 and 3. Section line 3—3 on Figure 4 indicates the cross section of Figure 3.

30 By referring to the drawings and Figures 1 and 2 in particular it will be seen that a railroad track is disclosed which comprises a plurality of ties 10—10 and a pair of spaced rails 11—11. The ties 10 in the area of the crossing are provided with spacing members 12 which are

35 positioned longitudinally on each of the ties and secured thereto by suitable means, not shown. A plurality of resilient pads, generally indicated by the numeral 13, are positioned on the spacing members 12, each of the pads 13 being of a length extending from rail to rail and having 40 longitudinally extending flanges 14—14 on their outermost ends. The flanges 14 are preferably tapered outwardly and terminate in abutting relation to the rails 11.

The main body of the resilient pad 13 is positioned inwardly in spaced relation to the rails 11 by the flanges 45 14, the space between the main body of the pad 13 and the rails 11 comprising flangeways for the flanges on the wheels of the railroad equipment.

Each of the resilient pads 13 incorporates a transversely corrugated metal back 15, the ends of which are doubled inwardly as at 16 and which terminate well within the end areas of the resilient pad 13 so that the flanges 14 extending beyond the ends of the pads 13 are completely flexible and capable of being deflected as in the event foreign materials enter the flangeways and are positioned downwardly against the flanges 14 by the flanged wheels 50 of the operating equipment.

The combined height of the resilient pad 13 and the spacing member 12 is substantially equal to the total height of the rails 11. It will occur to those skilled in the art that the railroad crossing structure is thus capable of use with any of the various sized rails in use by the several railroads as the thickness of the spacing members 12 may be varied to match the over-all height of the rail when in the assembly.

55 It will occur to those skilled in the art that a plurality of the pads 13 positioned on the spacing members 12 transversely of the railroad track and between the rails 11—11 and in edge to edge relation will form a suitable crossing structure and will be self-retaining with respect to the rails.

60 70 If desired, the pads 13 can be anchored to the track structure by positioning spikes, screws or other fasteners

through openings 17—17 provided and disclosed in detail in Figures 2, 3 and 4 of the drawings. By referring thereto it will be seen that the openings 17 extend through the resilient portion of the pads 13 and through the metal back 15 and that a flanged grommet 18 having a resilient sleeve 19 therein is positioned in the opening 17 in the metal back so that a fastening member such as a spike 20 positioned through the opening 17 and into the spacing member 12 will resiliently hold the pad 13 in relation thereto.

The upper surface of the resilient pad 13 is preferably formed with a combination drainage and traction tread pattern comprising a plurality of raised areas 21 defined by a plurality of channels 22, as best shown in Fig. 4 of the drawings.

It will be observed that the end portions of the pad 13 comprise transversely extending solid bar sections 23 providing shoulders on the ends of the resilient pad 13 adjacent the flangeways formed by the longitudinal flanges 14, as heretofore described.

It will occur to those skilled in the art that similar resilient pad structures may be positioned on the outer ends of the ties 10 beyond the rails 11 to complete the crossing, and in the event of double tracks such resilient pads may be positioned between the outer rails of the respective double tracks.

In Figure 2 of the drawings a secondary spacing member 12A is shown on the ends of the tie 10 and a secondary resilient pad 13A positioned thereon.

It will occur to those skilled in the art that the railroad crossing structure disclosed herein and specifically the resilient pad 13 with its reinforcing metal back 15 is capable of other uses and specifically bridge floors and industrial floors where suitable supporting base structures are supplied. Bridge floors now using metal grids which ice up in cold weather may be effectively re-surfaced with the resilient pad to provide a safe non-skid, non-icing wearing surface.

Industrial hand trucks and trailers used in industrial plants cut up conventional floors and the installation of the resilient pad with steel reinforcing back, as shown herein, eliminates such further floor destruction and at the same time cushions the load and reduces damaging otherwise caused in transit to the equipment and the material transported.

In such installations on bridge floors and for industrial flooring, the longitudinally extending edge flanges 14—14 are eliminated and the pads positioned in adjacent side-by-side relation.

It will thus be seen that the structure disclosed herein can be used for forming the complete railroad crossing whether a single track, double track or multiple track crossing is involved, and that the resulting crossing will possess the desirable characteristics of light weight, easy installation and removal for track inspection and repair and at the same time be resiliently yieldable so as to move with the railraod track without effecting the smooth rail top level crossing provided.

It will thus be seen that the railroad crossing structure disclosed herein meets the several objects of the invention.

Having thus described my invention, what I claim is:

1. A railroad crossing pad comprising a thick section of rubber-like resilient material having longitudinally extending flanges on the opposite side edges thereof, a metal plate embedded in said pad, the opposite side edges of said metal plate being spaced inwardly of said pad with respect to said flanges, said metal plate having a plurality of corrugations extending transversely of said pad and parallel with said flanges and acting to render said pad semi-rigid in one direction and flexible in another direction.
2. The railroad crossing pad set forth in claim 1 and wherein the resilient material and metal plate have a plurality of spaced openings formed therein and wherein grommets having resilient tubular liners are positioned in said openings to define passageways through which fasteners may be positioned.
3. The railroad crossing pad set forth in claim 1 and wherein the metal plate embedded therein is positioned adjacent the bottom thereof.
4. The railroad crossing pad set forth in claim 1 and wherein said corrugations in said metal plate have their upper and lower surfaces flattened transversely so as to define a plurality of spaced parallel alternate oppositely disposed channels therein.
5. The railroad crossing pad set forth in claim 1 and wherein the section of rubber-like resilient material is vulcanized to said metal plate.
6. A railroad crossing pad comprising a corrugated metal plate having its longitudinally extending opposite side edges doubled inwardly, a section of rubber vulcanized to the upper surface of said corrugated metal plate, said section of rubber having a bottom surface shaped to match said upper surface of said metal plate and a flat upper surface, a secondary section of rubber vulcanized to the lower surface of said corrugated metal plate, longitudinally extending flanges on the opposite side edges of said sections of rubber, said opposite side edges of said section of rubber and said flanges extending beyond said side edges of said metal plate.
